UNITED STATES PATENT OFFICE.

DAVID WILLIAMS, OF ALGIERS, LOUISIANA.

SPRINKLER HEAD FOR FIRE-EXTINGUISHING SYSTEMS.

Application filed February 14, 1923. Serial No. 618,994.

To all whom it may concern:

Be it known that I, DAVID WILLIAMS, a citizen of the United States, residing at Algiers, in the parish of Orleans and State of Louisiana, have invented certain new and useful Improvements in Sprinkler Heads for Fire-Extinguishing Systems, of which the following is a specification, reference being had to the accompanying drawings.

10 This invention relates to improvements in sprinkler heads for fire extinguishing systems and more particularly to the construction of the fusible link usually employed in conjunction with such sprinklers.

15 An important object of the invention is to provide a sprinkler head, the link of which is under tension and the parts of which will accordingly separate rapidly when the fusible section thereof is destroyed by heat.

20 A further object of the invention is to provide a fusible link which is constructed of two pieces of metal exactly similar in construction and which accordingly may be very cheaply produced.

25 A still further object of the invention is to provide a sprinkler head the parts of which are reduced to a minimum.

These and other objects I attain by the construction and arrangement shown in the 30 accompanying drawings wherein for the purpose of illustration is shown a preferred embodiment of my invention and wherein like reference characters designate like parts throughout.

35 In the drawings:—

Figure 1 is a view partially in section of a sprinkler head embodying a fusible link constructed in accordance with my invention;

40 Figure 2 is a perspective of the assembled link;

Figures 3, 4 and 5 are perspective views of the parts of the links when separated; and

45 Figures 6 and 7 are views of the blanks from which the sections shown in Figures 3 and 5 are constructed.

Referring now more particularly to the drawings, the numeral 10 designates a nipple 50 adapted to be inserted in the sprinkler pipe and which is formed at its upper end with a valve seat 11 which coacts with a valve 12 to close the outlet of fluid through the nipple. The nipple is provided at opposite 55 sides thereof with upwardly extending arms 13 which are joined at their upper ends by

a bridge piece 14 overhanging the valve 12. This bridge piece has a threaded central aperture 15 through which is directed a threaded member 16, the upper end of which is adapted for engagement by a wrench, as indicated at 17, and the lower end of which is provided with a socket for engaging the upper end of a fusible link 18, the lower end of which engages against the valve to hold the same in position on the seat. This threaded member 16 is formed above the bridge piece 14 with a spray head 19 against which water emerging from the nipple 10 will engage to be dispersed in the form of a spray.

The fusible link 18 is in the form of a trapezoid having a notch 20 formed in the base thereof. The link as a unit may be divided into two sections, a fuse section 21 and a stem section 22, which are differentiated by the fact that the fuse section has the parts thereof connected by a layer of fusible metal 23 whereas the stem section 22 contains no fusible metal. The stem section 22 is split from the base of the notch 20 about its point of juncture about the fuse section 21, as indicated at 24.

The fuse section is composed of two flat sheets of metal 25 and 26 joined by the 85 fusible layer 23 above noted, each of the sheets 25 and 26 being connected with a corresponding stem section 25^a or 26^a into which the stem seat of the trapezoid is divided by the split 24 above mentioned. The 90 sections 25^a and 26^a are of a thickness equal to the combined thickness of the sheets 25 and 26 and interposed connecting layer of fusible material 23. The sheets 25 and 26 are correspondingly curved, as at 27, so that 95 they interfit, this curvature being in a direction transverse to the line of movement of the sheets 25 and 26 induced by applying pressure to the corners 28 of the stem side of the link when the fusible layer 23 100 is removed by heat or otherwise. These sections being curved and interfitting, will by such movement be caused to separate and it will be obvious that such separation will remove the supporting coaction between 105 separate sections of the link causing the same to fly apart under the pressure applied thereto and to permit the valve 12 to elevate from its seat under the pressure of water from the fire line F. The sections 110 from which the link is formed may be produced in any desired manner. The sheets

25 and 26 are provided with an extension E which is composed of three sections S, S¹ and S², each section corresponding in shape to a part 25^a or 26^a of the stem side 22, the 5 sections having corresponding parts thereof joined and being adapted to be folded at the juncture of these corresponding points, as indicated by the dotted lines, to form a structure such as shown in Figure 2. Being 10 constructed in similar parts, the link may be readily produced and assembled, thereby reducing the cost thereof to a minimum. It will be obvious that by adjusting the part 16 toward the cap, a desired tension 15 may be placed upon the sections of the link and that upon release of these sections by fusing of the fusible layer, these sections will move in opposite directions to release the valve. It will furthermore be 20 obvious that the construction as hereinbefore set forth is capable of some change and modification without materially departing from the spirit of my invention and I accordingly do not limit myself to such 25 specific structure except as hereinafter claimed.

I claim:

1. A fusible link for the sprinkler heads of sprinkler systems having a closure valve 30 and a part adjustable toward the closure valve comprising a member having a fuse section and a stem section, the stem section being divided intermediate its length into two parts constructed to rock upon one another when pressure is applied to the ends 35 thereof, the fuse section comprising a pair of sheets, each sheet being provided with an extension forming one section of the stem section, and a fusible connection between 40 said sheets.

2. A fusible link for the sprinkler heads of sprinkler systems having a closure valve and a part adjustable toward the closure valve, comprising a member having a fuse 45 section and a stem section, the stem section being divided intermediate its length into

two parts constructed to rock upon one another when pressure is applied to the ends thereof, the fuse section comprising a pair 50 of sheets, each sheet being connected to one section of the stem section, and a fusible connection between said sheets, said sheets being correspondingly curved in a direction transverse to the direction of movement 55 thereof upon rocking of the stem section under pressure applied thereto when the sheets are released whereby upon fusing of the fuse section the stem sections are caused to rotate upon one another to assist in the separation thereof.

3. A fusible link for the sprinkler heads of sprinkler systems having a closure valve and a part adjustable toward the closure valve comprising a fuse section and a stem section, the stem section being adapted for 60 engagement with the closure valve and said part at its upper and lower faces adjacent the end edge thereof, said end edge of the stem section being provided centrally with a notch and being split at the base of the 65 notch in two sections, the fuse section comprising a pair of sheets fusibly connected to one another and each rigidly connected with 70 one of said stem sections.

4. A fusible link for the sprinkler heads of sprinkler systems having a closure valve and a part adjustable toward the closure valve, comprising a fuse section and a stem section, the stem section being adapted for 75 engagement with the closure valve and said part at its upper and lower faces adjacent the end edge thereof, said end edge of the stem section being provided with a notch, the stem section being split at the base of 80 the notch to form the same in two sections, the fuse section comprising a pair of sheets 85 fusibly connected to one another and each having an extension formed to provide one section of said stem section.

In testimony whereof I hereunto affix my 90 signature.

DAVID WILLIAMS.
